UNITED STATES PATENT OFFICE.

FLOYD W. KING, OF CLIFTON FORGE, VIRGINIA, ASSIGNOR TO COVINGTON MACHINE COMPANY INC., OF COVINGTON, VIRGINIA, A CORPORATION OF VIRGINIA.

WINDOW PLATFORM.

Application filed November 12, 1925. Serial No. 68,595.

This invention relates to window platforms used for cleaning, painting, repairing or other uses, and comprises all improvements over the prior art which are disclosed in this application. Some objects are to provide an economically constructed platform which will be readily usable on different buildings with a minimum of adjustment, which will be reliable, strong, of minimum weight and firmly placed in use, and which can be shifted from window to window of a given building without adjustment.

The above and other objects which will hereinafter appear, are attained by new and useful improvements as disclosed in this application. To enable others skilled in the art to fully understand the essential features of the improvements, drawings have been annexed as a part of this disclosure.

Fig. 1 is a side elevation of the window platform applied to a window sill shown.

Fig. 2 is a right end view of Fig. 1.

The particular embodiment of the invention which is herein disclosed for illustrative purposes, comprises a supporting frame preferably consisting of two pairs of parallel T-iron members 1 which may be integral at one end 2 and connected at the other end by plates 3. The lower members 1 rest upon window frame 4. Each bracket plate 6 may consist of sheet metal folded to form a portion of a hinge 7 and secured on opposite sides of flanges 8 of members 1 by rivets 5. Each bracket 9 is of sheet metal and folded to complete the hinge 7 and has its two portions riveted together at 10. Laterally bent flanges 11 form a supporting foot means 12 which slopes upwardly and inwardly toward the interior of the building and is adapted to rest on the extreme outer portion of window sill 13. The lower portion of bracket 9 has flanges 14 adapted to engage against the outer surface of the wall of building 15.

Each clamp member 16 may comprise two pieces of sheet metal slidably engaging the opposite sides of flanges 8 of members 1 and connected together by rivets 17. Screw 18 rotates in a shaped socket 19 formed between the sheets of bracket plate 6 and in a hole formed between plates 3, being held against longitudinal movement by collars 20, 20 on opposite side of plates 3. A cut out 21 in clamp member 16 is occupied by nut 22 threaded on screw 18 and the nut is held

against rotation by engagement of its angular sides against the top and bottom of cut out 21. Thus as screw 18 is rotated by handle 23 in one direction or the other, clamp member 16 is moved forward or backward. Clamp member 16 has an upwardly inwardly sloping flanged clamping surface 24 and a vertical flanged clamping surface 25.

Platform 26 preferably of wood is secured on top of the two top members 1. Connected on the underside of platform 26 at the center is a cross brace 27 secured to lower members 1. Tie-brace 28 is connected to bracket plates 6 to give increased strength and rigidity.

A folding metal frame back 29 which may be folded down as indicated in dotted lines, preferably has canvas sides 31 and back 32 with any desired number and size of pockets 33 for holding cleaning materials, tools, etc. If desired, such surfaces of the device as are to come into contact with the parts of a building may be covered with rubber or felt.

Operation: The lower members 1 are rested on window frame 4. The brackets 9 are swung down as indicated by dotted line 34 (Fig. 2) from folded position to their vertical position as shown in Figs. 1 and 2, and the screws 18 are turned to force clamp members 16 against the inside structure of the building until supporting feet 12 properly engage window sill 13. Folding back 29 is opened up and the device is ready for use. In some buildings surface 24 will engage the inner lower edge of the window frame 4 as shown. In other cases surface 25 will be the engaging surface. As parts 12 rest firmly upon the outer edge of window sill 13, the device is firmly supported at a maximum distance out, thus reducing springing and breaking stresses upon the device to a minimum and permitting the use of relatively light weight construction materials. It is also to be noted that as brackets 9 are non-adjustable longitudinally of members 1, the device always projects out of a building a fixed or set distance, irrespective of different thicknesses of building walls. Therefore the fulcrum of parts 12 on the window sill 13 is always constant and the platform will support its maximum weight on any thickness of window sill or ledge. After having adjusted clamp members 16 for

a window of a given building, the windows being all alike, to then shift the device from one window to another it is merely necessary to grasp the frame on opposite sides 5 with both hands at 35 and tilt it upward and inward sufficiently so that brackets 9 can be folded up to clear sill 13 when the device can be drawn in sufficient to clear clamp members 16 from the inner wall structure of 10 the building. The device is then placed out through another window opening and while tilted and with clamp members 16 engaged against the inner wall structure, the brackets 9 are swung down to vertical position and 15 the device is permitted to properly locate itself, which it does without requiring any adjustment.

All changes which properly come within the spirit and range of equivalency of the 20 following claims are intended to be embraced within the scope of the claims.

I claim:

1. A window platform including, a supporting frame adapted to extend through a 25 window opening and rest upon a window

frame, said supporting frame including substantially parallel members arranged in spaced relation one above another, said upper and lower members each having a guide flange extending toward each other, supporting means secured to said supporting frame and adapted to engage the outer portion of a building, and anchoring means slidably engaging said guide flanges and adapted to be adjusted longitudinally thereof and engage the inner portion of a building. 30

2. The window platform of claim 1 in which the anchoring means slidably engages the opposite sides of the guide flanges. 35

3. The window platform of claim 1 in which the anchoring means includes two sheet metal pieces which slidably engage the opposite sides of the guide flanges. 40

4. The window platform of claim 1 in which the supporting means includes two sheet metal pieces which span and are secured to, opposite sides of the upper and lower guide flanges. 45

FLOYD W. KING.
